Primary Examiner—Philip S. Hyder(74) *Attorney, Agent, or Firm*—Finnegan, Henderson, Farabow, Garrett & Dunner, L.L.P.(57) **CLAIM**

The ornamental design for a prone torso exerciser, as shown and described.

DESCRIPTION

FIG. 1 is a perspective view of a prone torso exerciser embodying our design;

FIG. 2 is a top plan view thereof;

FIG. 3 is a bottom plan view thereof;

FIG. 4 is a left side elevational view thereof;

FIG. 5 is a right side elevational view thereof;

FIG. 6 is a front elevational view thereof; and,

FIG. 7 is a rear elevational view thereof.

The features shown in dashed lines in FIGS. 1-7 are for illustrative purposes only and form no part of our design.
